UNITED STATES PATENT OFFICE.

HENRY NOARK AND SAMUEL C. DUKE, OF WALLER, TEXAS.

VENDING-MACHINE.

1,192,338.

Specification of Letters Patent.

Patented July 25, 1916.

Application filed October 26, 1915. Serial No. 57,931.

To all whom it may concern:

Be it known that we, HENRY NOARK and SAMUEL C. DUKE, citizens of the United States, residing at Waller, in the county of Waller and State of Texas, have invented certain new and useful Improvements in Vending-Machines, of which the following is a specification.

This invention relates to new and useful 10 improvements in vending machines.

The object of the invention is to provide a device of the character described adapted for the purpose of vending liquids such as gasoline, oils and the like.

15 Another object of the invention resides in the construction whereby a fixed value of the commodity will be delivered to the purchaser, the construction being so arranged that the quantity delivered may be varied in 20 accordance with variation in prices.

A further feature of the invention resides in the provision of a register whereby the value of the entire quantity delivered will be indicated.

25 A still further feature of the invention resides in the provision of a mechanism whereby different quantities of the commodity may be delivered in accordance with the amount desired; and the invention also comprehends 30 a construction whereby spurious coins when inserted will be thrown out without tripping the operative mechanism and causing a delivery.

With the above and other objects in view 35 the invention has particular relation to certain novel features of construction, operation and arrangement of parts an example of which is given in this specification and illustrated in the accompanying drawings 40 wherein;

Figure 1 is a side elevation of the device, Fig. 2 is an end view thereof, Fig. 3 is a transverse sectional view, Fig. 4 is a fragmentary vertical sectional view, Fig. 5 is a fragmentary plan view of the registering device, Fig. 6 is a plan view thereof showing the reverse side from that shown in Fig. 5, Fig. 7 is a sectional view thereof, taken on the line $a-a$ of Fig. 6, Figs. 8 and 9 show 50 top and bottom views respectively of an air inlet valve employed, Fig. 10 shows a plan view of the coin controlled mechanism, Fig. 11 shows a vertical sectional view thereof, Fig. 12 shows a transverse vertical sectional view thereof, taken on the line $b-b$ of Fig. 11, Fig. 13 shows a horizontal sectional 55 view thereof taken on the line $c-c$ of Fig. 1.

view thereof taken on the line $c-c$ of Fig. 11, and Figs. 14 and 15 show fragmentary sectional views of said mechanism.

Referring now more particularly to the drawings wherein like numerals of reference designate similar parts in each of the figures the numeral 1 refers to an inclosing casing wherein the operative mechanism is inclosed. Mounted in this casing are a plurality of containers 2, 3 and 4 preferably cylindrical in form and which contain the commodity to be sold. An auxiliary container 5 is provided which is connected to the container 2 through the pipe 6. This last mentioned container may of course be dispensed with and is provided only for the purpose of increasing, in effect, the capacity of the container 2. An inlet pipe 7 leads from a suitable source of supply and communicates with said containers through which they are supplied with the liquid and leading from said container is the discharge pipe 8. These pipes are controlled by suitable two way valves 9, 10 and 11 respectively of the ordinary construction which it is not thought necessary to specifically describe, said valves being controlled through the transverse shafts 12, 13 and 14 respectively, as will hereinafter be explained so that when the inlet pipe to any particular container is opened the discharge pipe leading therefrom will be closed and vice versa. These shafts are rotatable in suitable bearings and on one side they have the arms 15, 16 and 17 fixed to their corresponding ends. To the free ends of these arms the respective links 18, 19 and 20 are pivoted at one end and to the other ends of these links the respective rods 21, 22 and 23 are adjustably secured. These rods are slidable through the coin block 24 which is slidable on a track formed of the rods 25 and 26 whose respective ends are secured to the casing. This block has the coin chutes 27, 28 and 29 extending vertically therethrough, of different dimensions so as to receive coins of different sizes in accordance with the amount of the commodity which it is desired to purchase. These chutes are arranged in alinement with the respective rods 21, 22 and 23.

Underneath the coin block are the receptacles 30 and 31 provided to receive the genuine and spurious coins respectively. In case a certain quantity of the commodity is desired a coin of the proper size will be inserted, for example, in the chute 2 and said

coin, which is indicated by the numeral 32 will drop down behind the enlarged head carried by the inner end of the rod 21 and the handle 33 carried by the coin block 24 may then be forced forwardly and said coin will lock against the end of said rod 21 and operating through the link 18 and the arm 15 will cause the shaft 12 to turn manipulating the valve 9 so as to open the discharge 10 pipe 8 and the quantity of liquid contained in the container 2 will be delivered. The coin block 24 should then be moved back to its original position and the pull thereof exerted through the rod 21, the link 18 and the 15 arm 15 will operate to again manipulate the valve 9 in the reverse direction to open the inlet and close the discharge pipe and the container 2 will again fill with the liquid. If coins are not inserted in the chutes 28 and 20 29, during this operation just described, the rods 22 and 23 will remain stationary, the block 24 sliding thereon and their enlarged heads passing through the passage ways as 34 in said block in alinement therewith. 25 Should coins be inserted in all of the chutes at the same time and the block 24 forced forwardly on its track all of the valves 9, 10 and 11 will be manipulated and the total amount of the liquid in the containers 2, 3 30 and 4 will be delivered. The enlarged heads of the rods 21, 22 and 23 are arranged to engage with the block 24 so that when it is moved back to its original position they will not disengage therefrom.

35 In case a coin smaller than that required is inserted in any slot it will drop on down through the alined slots 35, 36 or 37, as the case may be, cut through the transverse partition 38 forming the top of the coin receptacles and may be recovered, but when the proper sized coin is inserted it will lock against the enlarged head of the corresponding rod and will be carried forwardly. When the movement of the block 24 is reversed it will operate to slightly release the coin and when the same passes over the alined slot 38, 39 or 40, as the case may be, it will drop through said slot into the closed receptacle 30. Diverging from the respective chutes 27, 28 and 29 are the chutes 41, 42 and 43 provided for the passage way of spurious coins and at the entrance of the chutes on the sides from which the spurious coin chutes diverge are the magnets 44, 45 and 46. Spurious coins are usually formed of metal which is attracted by a magnet and when spurious coins of this character are inserted they will, by said magnets, be directed down the spurious coin chutes, and will pass through the slots 47, 48 or 49, as the case may be, cut through the partition 38, and will fall into the spurious coin receptacle 31.

45 Each of the containers is provided with a plunger as 50 connected to which is a hollow

shaft as 51 which passes through the stuffing box 52 carried by the container head and this plunger is manipulated up and down so as to vary the contents of the container, as the price of the commodity varies, through the hand screw 53 which is connected to the bracket 54 and through which the externally threaded portion of the shaft 51 passes. The upper end of each shaft 51 carries a cylinder 55 having the seat 56 therein which is normally closed by the valve 57. This valve seats upon the coil spring 58 whereby it is held closed. Upstanding from the valve 57 is the stem 59 which passes through the stuffing box 60 in the upper end 70 of the cylinder 55. The said upper end of said cylinder has a plurality of orifices 61 to admit air for a purpose to be hereinafter explained. Slidably mounted in vertically alined bearings is the rod 62 whose upper end carries a laterally extended arm 63 alined over the stem 59 and the lower end of this rod is turned at right angles forming a hook as 64. The corresponding ends of the shafts 12, 13 and 14 have arms as 65 fixed 85 thereon and when either of said shafts is turned, as hereinbefore explained, to effect a delivery of the liquid, its arm 65 will engage with the corresponding hook 64 and exert a downward pull on the rod 62 bringing the arm 63 into contact with the upper end of the stem 59 and thereby unseating the valve 57 whereby air is admitted to the corresponding container to prevent the formation of a vacuum therein. This rod 62 100 is normally held elevated through a pull spring, one end of which is attached thereto and the other end of which is secured to the stationary bar 66. As will be observed from an inspection of Fig. 1 each of the shafts 105 51 is provided with a gage and a slidable hand as 67, by the movement of which relative to the gage, the price of the commodity may be indicated.

110 A registering device has been provided to indicate the value of the commodity delivered from each of the containers, this device being shown in detail in Figs. 5, 6 and 7, which will now be described. Attached to the front side of the container is a circular 115 casing 68 having an oblong slot 69 cut therethrough and a central shaft 70 is provided whereon is rotatable the spur gear 71 which is integral with the annular disk 72 being connected thereto through the neck 73. This neck forms a bearing for the independently 120 rotatable annular disk 74 whose periphery is serrated and this disk has the numerals 5 and multiples thereof to 95 indicated thereon which pass under the outer end of the slot 69 as the disk 74 rotates. The corresponding face of the disk 72 has the numerals from 1 to 9 inclusive arranged around the rim thereof in a manner the reverse of the arrangement of the numerals of the disk 74, 130

said last mentioned numerals passing under the inner end of the slot 69. An idle gear wheel 75 is rotatably mounted upon the casing wall and in mesh with the gear wheel 71. 5 The rear face of the disk 74 carries a pin 76 arranged to contact with and impart a partial rotation to the gear wheel 75 with each rotation of the disk 74. As shown when one 10 dollars worth of the commodity has been sold the disk 74 will have made one rotation causing a partial rotation of the disk 72 and bringing the numerals 1 to 9 successively into view through the slot 69, said numerals denoting the number of dollars which have 15 been deposited in the coin receptacle. The disk 74 is rotated through a flexible finger 77, the lower end of which is attached to one side of the corresponding shaft 12, 13 or 14 and the upper end of which is held in engagement with the peripheral teeth of the 20 disk 74 through the pull spring 78, one end of which is attached to said finger and the other end of which is secured to the casing 68. As the corresponding shaft is turned to 25 open the valve and deliver the commodity an upward thrust is imparted to the finger 77 causing a partial turn of the disk 74. This disk is held against reverse movement by means of a flexible spring 79, one end of 30 which is attached to the casing 68 and the free end of which engages against the abrupt sides of said peripheral teeth. The marginal numerals on the disk 74 will, of course, vary in some cases quantities of the 35 value of five cents will be sold and in other cases twenty five cent or fifty cent quantities only will be sold and said numerals should be varied accordingly.

While we have shown only one form of 40 this device it is obvious that the mechanical structure thereof may be varied without departing from the principle of the invention and we hereby reserve the right to make such structural changes as may be found 45 necessary so long as we keep within the scope of the appended claims.

What we claim is:

1. In a device of the character described, 50 an actuating mechanism, a coin block slidably mounted and having a coin chute therein and operatively connected with said mechanism through the coin deposited in said chute, said block also having a diverting

chute through which spurious coins may pass without bringing the block into operative connection with said mechanism. 55

2. A device of the character described embodying a plurality of actuating mechanisms, a manually movable means having a plurality of coin chutes therein and which 60 is operatively connected with the corresponding mechanism through the coin placed in the chute corresponding to said mechanism to be operated and an indicating device actuated through said mechanism 65 and indicating the denomination of the coin deposited in the corresponding chute.

3. A valve operating mechanism embodying a slidably mounted block having a coin chute therein, an operating rod, one end of 70 which projects through said block but which is locked against movement relative to the block by means of the coin placed in said chute, said block also having a diverting chute through which spurious coins may 75 pass without bringing the block into operative connection with said rod.

4. A valve operating mechanism embodying an operating rod, a means slidably mounted on said rod and having a coin 80 chute provided to receive a coin which locks said means against movement relative to the rod, and also having a coin diverting chute through which spurious coins may pass without locking said means against movement relative to the rod. 85

5. A valve operating mechanism embodying an operating rod, a means slidably mounted on said rod and having a coin 90 chute provided to receive a coin which locks said means against movement relative to the rod and also having a coin diverting chute through which spurious coins may pass without locking said means against movement relative to the rod, and a magnet arranged 95 so as to attract said spurious coins into said diverting chute.

In testimony whereof we have signed our names to this specification in the presence of two subscribing witnesses.
